RECTIFIER CONTROL SYSTEM

Didier Journeaux, Wauwatosa, Wis., assignor to
 Allis-Chalmers Manufacturing Company, Milwaukee, Wis., a corporation of Delaware

Application April 29, 1933, Serial No. 668,498
 Renewed November 14, 1936

49 Claims. (Cl. 175—363)

This invention relates to improvements in control systems, and more particularly to a system for limiting the current within an electron discharge device to a value which the device is in condition to carry at the instant considered, without danger of damage thereto or of faulty operation thereof.

It is known that, in an electron discharge device of the vapor type in which the vapor is supplied from the cathode material, the arc drop within the device depends upon the conditions of pressure and temperature of the vapor carrying the arc. It is desirable to always maintain the arc drop at a low value because a high arc drop decreases the efficiency of the device, may cause deterioration or destruction of the device by localized liberation of excessive heat, may cause failure of the control electrodes to function and may also result in oscillations or other disturbances in the circuits associated with the device. The arc drop may reach an excessive value when the walls of the device are too cold so that the vapor produced at the cathode condenses on the walls too rapidly and does not leave a sufficient amount of vapor available for ionization in the arc path. The result of such condensation is that the electronic space charge is not sufficiently neutralized by the amount of ionizable vapor present and the arc drop reaches a value intermediate that of a normally operating vapor device and that of a device of the vacuum type. Such condition may arise when cooling means associated with the device are adjusted for maintaining the temperature thereof at too low a value or else when the device, after carrying an amount of current for which its temperature is adequate, is suddenly required to carry a larger amount of current for which its temperature is too low. It is then necessary either to disconnect the device from the associated circuits, or to provide a larger amount of vapor within the device, or to reduce the amount of current flowing therethrough to prevent the continued operation of the device under conditions producing a high arc drop. Such results can be obtained by means of a system responsive to the magnitude of the arc drop, which preferably utilizes voltage responsive means connected between one anode and the cathode of the device over an auxiliary electron discharge device. The connections are then preferably such as to impress the voltage between anode and cathode of the device on the voltage responsive means only while the anode is carrying current. Under the most favorable operating conditions, as is well known, the value of the arc

drop normally varies with the amount of current carried by the device and it is therefore advantageous to provide an automatic adjustment of the voltage responsive circuits in response to the amount of current flowing through the device. 5

It is therefore among the objects of the present invention to provide a control system for electron discharge devices which system is responsive to the variations of the magnitude of the arc drop within the device. 10

Another object of the present invention is to provide a control system for electron discharge devices which system is responsive to the peak value of the arc drop within the device. 15

Another object of the present invention is to provide a control system for electron discharge devices which system is responsive to the value of the voltage between one anode and the cathode of the device only during the periods when the anode is carrying current. 20

Another object of the present invention is to provide a control system for electron discharge devices which system employs one or more auxiliary electron discharge devices. 25

Another object of the present invention is to provide a control system for electron discharge devices in which the system is automatically variably adjusted in response to the magnitude of the current flowing through the device. 30

Another object of the present invention is to provide a control system for electron discharge devices for interrupting the flow of current through the device when the arc drop within such device reaches a value greater than the normal operating value thereof. 35

Another object of the present invention is to provide a control system for electron discharge devices whereby the amount of vapor produced within the device may be increased when the arc drop within the device reaches a value greater than the normal operating value thereof. 40

Another object of the present invention is to provide a control system for electron discharge devices operable to regulate the flow of current through the device in response to the variations of the arc drop within such device. 45

Another object of the present invention is to provide a control system for electron discharge devices operable to variably energize the control electrodes of the device in response to the variations of the arc drop within such device. 50

Objects and advantages other than those above set forth will be apparent from the following description when read in connection with the accompanying drawings, in which: 55

Fig. 1 diagrammatically illustrates one embodiment of the present invention operable to disconnect an electron discharge device of the vapor type, which is operable as an alternating current rectifier, from the supply line thereof when the average arc drop within such device exceeds, by a predetermined amount, the value of the arc drop of an auxiliary device having the arc drop therein adjusted in response to the value 10 of the current flowing through the main device;

Fig. 2 diagrammatically illustrates, the portions differing from the embodiment of Fig. 1, of a modified embodiment of the present invention differing from the embodiment illustrated 15 in Fig. 1 in that the amount of exciting current of the device is regulated in response to the variations of the value of the arc drop and the device is not disconnected from the supply line upon change in the arc drop;

Fig. 3 diagrammatically illustrates the modified portions of another modified embodiment of the present invention differing from the embodiment illustrated in Fig. 2 in providing means for supplying vapor to the device in response to the 25 variation of the arc drop within such device;

Fig. 4 diagrammatically illustrates another embodiment of the present invention whereby the current within the device is regulated in response to the variations of the peak value of 30 the arc drop within the device;

Fig. 5 diagrammatically illustrates another embodiment of the present invention whereby the control electrodes of the device are variably energized, in response to the variation of the 35 average arc drop, to control the flow of current within such device;

Fig. 6 diagrammatically illustrates the modified portions of a modified embodiment of the present invention differing from the embodiment 40 illustrated in Fig. 5 in the method of connecting the voltage responsive circuits;

Fig. 7 is a diagram of the voltage relations between one anode and the cathode of the device illustrated in Figs. 1 to 4;

Fig. 8 is a diagram of the voltage between one anode and the cathode and of the voltage of a current transformer receiving the current of the same anode of the device illustrated in Figs. 5 and 6;

Fig. 9 is a characteristic curve of some of the auxiliary discharge devices utilized in the different embodiments illustrated; and

Fig. 10 diagrammatically illustrates another embodiment of the present invention in which 55 the control electrodes of the device are variably energized in response to the variations of the peak value of the arc drop within such device.

Referring more particularly to the drawings by characters of reference, reference numeral 11 designates an alternating current line, herein 60 shown as a three phase line only for the reason that such type of line is most frequently utilized in practice. Line 11 is utilized as a supply line for an electron discharge device 16 connected therewith by means of a transformer having a primary winding 12 and a secondary winding 13. Winding 13 preferably comprises a plurality of star connected portions severally connected with the anodes 14 of device 16. The cathode 17 of device 16 is connected with one conductor 18 of a direct current line having the second conductor 19 thereof connected with a neutral point of winding 13. In the embodiment illustrated in Fig. 1, the flow of current through device 70 75 16 may be interrupted by means of a circuit

breaker 21 herein shown as being inserted in the connection between winding 12 and line 11. It will be understood that such circuit breaker could also be inserted in the connections between winding 13 and anodes 14 or in conductors 18 and 19, opening of such circuit breaker resulting, in each case, in interruption of the flow of current within device 16. Circuit breaker 21 tends to open under the action of a spring 22 and is normally retained in the closed position by a latch 23 which may be released by a solenoid or trip coil 24.

For the purpose of obtaining a circuit responsive to the variations of the voltage between one anode 14 and cathode 17, one of such anodes 15 is connected through a battery 25 with the anode 26 of an electron discharge device 27 having a cathode 28. Device 27 is preferably of the gas or vapor type and the operating vapor therein may be supplied by a drop of mercury 29. Cathode 28 may be of the incandescent type heated by the current of a battery 31, such current being adjusted by means of a rheostat 32. Cathode 28 is connected with conductor 18 over a rheostat 33, a meter 34 and the coil 36 of a time delay 20 relay 37. Relay 37 is operable to close contacts 38 to connect a battery 39 with trip coil 24; current flowing in rheostat 33 and coil 36 may be measured by the indicating or recording instrument 34. As is well known, the arc drop within 30 a device such as device 27 is smaller than the arc drop within device 16, and also varies to a large extent in dependence upon the temperature. The temperature of device 27 is preferably maintained constant by means of a heater 41 receiving current from a suitable source such as battery 39, such current being controlled by a thermostat such as a bimetallic strip 42. A rough adjustment of the current in heater 41 may be obtained by a rheostat 43. To regulate 40 the flow of current through device 27 in response to the amount of current flowing through device 16, the operation of thermostat 42 may be controlled by a second thermostat 44 maintained at a variable temperature by heater 46 45 energized in response to the value of current flowing through device 16 by means of a shunt 47 in circuit in conductor 18.

In operation, assuming the system to be connected as shown in Fig. 1 and line 11 to be energized, each of the anodes 14 of device 16 receives an alternating voltage from the associated portion of winding 13. Such voltage is represented in Fig. 7 by a curve 48 drawn with respect to line 49 representing the voltage of cathode 17 as the reference line. As will be seen from Fig. 7, the voltage represented by curve 48 is positive and has an approximately constant value during the active period of operation of anode 14 and is variably negative during the idling period of such anode. In Fig. 7, the distance between line 49 and line 51 represents the arc drop within device 27 which drop may be considered as substantially constant even when such device receives variable currents, provided such currents are limited in 55 value within a predetermined range. When the voltage represented by curve 48 is greater than the voltage represented by line 51, a pulsating current will flow from anode 14 over battery 25 and anode 26 to cathode 28 of device 27, over rheostat 33, meter 34, and coil 36 to conductor 18, in parallel with the arc between anode 14 and cathode 17. The magnitude of such current is 60 proportional to the cross hatched areas 52 in Fig. 7 and is dependent upon the average value of the 65 70 75 75

arc drop between anode 14 and cathode 17 represented by the positive ordinates of curve 48. In the above consideration, the voltage of the battery 25 was not taken into account. By adjusting such voltage at a value substantially equal to the voltage drop within device 27 and opposed thereto, the flow of current through device 27 is substantially unaffected by such two voltages and is then substantially proportional to the entire areas bound by the positive portions of curve 48 and also, therefore, to the average voltage drop within device 16. Assuming that for any reason, the arc drop in device 16 increases over the value previously considered, such increased arc drop causing application of a higher potential to anode 26, the current flowing from anode 14 over device 27 will increase correspondingly and, upon reaching a predetermined value, will cause coil 36 to attract armature of relay 37 to close contacts 38 thereof. Such closure is effected, however, only if such flow of current is continued over a predetermined period of time necessary for the operation of the time delay mechanism of relay 37. Such time delay is desirable to prevent closure of contacts 38 upon occurrence of a transient increase of the arc drop in device 16 which would not necessitate interruption of the operation of device 16.

If the increase of the arc drop considered above is commensurate with an increase in the value of the current carried by device 16, such increase in the current will cause a larger current to flow through heater 46, thereby causing thermostat 44 to move out of engagement with the contact of thermostat 42. Thermostat 42 is thereby adjusted to maintain device 27 at a temperature lower than previously obtained. The arc drop in device 27 then increases as the temperature of such device becomes lower, thereby maintaining the flow of current therethrough at a low value and preventing the operation of relay 37. By means of the system illustrated, the flow of current through the device is thus interrupted only when the arc drop within such device reaches a value which is in excess of a value commensurate with the value of the current flowing through the device. As heater 46 and thermostat 44 are however necessarily endowed with thermal inertia, the heating of thermostat 44 by heater 46 cannot follow rapid variations of the current flowing through device 16 and shunt 47. If such current increases from a relatively low value to a relatively high value, thus causing the arc drop in device 16 to increase, at first the arc drop in device 27 remains adjusted to the initial value thereof. If the rate of change of the current in device 16 is relatively low, the response of the adjustment of the arc drop in device 27 by the action of heater 46, although lagging behind the change of current in device 16, is never materially different from the steady state adjustment thereof. If however the rate of change of the current in device 16 is relatively high, as the result for example of a short circuit in line 18, 19, the operation of device 27 is completely readjusted in response to the increased value of such current after a time delay such that, in the meanwhile, relay 37 may operate in response to the increase in the arc drop in device 16. Device 16 is thus protected against any damage which might be caused therein by the flow of short circuit current therethrough. In a general manner, the operation of device 27 and, therefore, the operation of relay 37 is variably adjusted in dependence upon

the rate of change of the flow of current through device 16.

In the embodiment partially illustrated in Fig. 2, it is assumed that the arc within device 16 is maintained by means of two excitation anodes 53 supplied over resistances 54 from an excitation transformer 56 energized from line 11. The amount of excitation current flowing through device 16 is regulated by adjusting the amount of resistance in the circuit of such excitation anodes, such resistance comprising a fixed resistance 57 and resistance 58 which may be short circuited over contacts 38 of relay 37. In the present embodiment, when the arc drop in device 16 reaches a value greater than the normal value commensurate with the value of the current flowing through such device, relay 37 closes contacts 38 and thereby short circuits resistance 58. The amount of excitation current flowing between excitation anodes 53 and cathode 17 is thereby suddenly increased and results in the production of a larger amount of operating vapor from cathode 17. Such increased production of vapor results in an increase of the vapor pressure within device 16 which tends to reduce the arc drop within such device to the normal value thereof.

In the embodiment partially illustrated in Fig. 3, device 16 is associated with a heating chamber 59 receiving operating material from cathode 17. Chamber 59 is in communication with a vapor distributor 62 conducting the operating vapor produced within such chamber to the space adjacent anodes 14, where such vapor escapes through openings 63 in pipe 62. Chamber 59 is preferably heated by a heating resistance 61 energized from battery 39 over contacts 38. When the arc drop within device 16 reaches a value which is excessive according to the standard defined above, relay 37 causes resistance 61 to receive current from battery 39 over contacts 38 thereby causing the production of vapor which is conducted in the space adjacent anodes 14. Such vapor is utilized for the complete ionization of the arc path, and the arc drop within device 60 is thereby restored to the normal value thereof.

In the embodiment illustrated in Fig. 4, the flow of current through device 16 is controlled by a plurality of reactors 78, 79 and 81 which may be given variable values of inductance by saturation of the cores thereof by means of a plurality of direct current saturating windings 74, 76 and 77. In the present embodiment, the current flowing through device 27 is utilized for charging a condenser 64 connected between cathode 28 and conductor 18. Rheostat 33 is then adjusted to a high value so that the current flowing over such rheostat between successive cycles of the voltage of line 11 does not appreciably decrease the charge of condenser 64. Cathode 28 is connected with the cathode 69 of an electron discharge device of the high vacuum type having the grid 66 thereof connected with conductor 18 over a bias battery 72 and a protective resistance 73. Cathode 69 is preferably of a type similar to that of cathode 28 and may be energized from battery 31 over a rheostat 71. The anode 68 of device 67 is connected with cathode 69 over a circuit including a plate battery 82, a rheostat 83 and coils 74, 76 and 77. Such circuit may also include the resistance element 86 of a carbon pile regulator 84 having an operating solenoid 87 energized from shunt 47 over a rheostat 89. The action of solenoid 87 is opposed by a spring 88 as is well known in the art. If the voltage between anode 14 and cathode 17 during the idling period of such anode, repre-

sented by the negative portion of curve 48 of Fig. 7, is greater than may be safely applied between anode 26 and cathode 28, a suitable device such as a glow tube 91 may be connected between anode 26 and conductor 18. Such device should be so selected as not to conduct current when receiving the arc drop between anode 14 and cathode 17, but to conduct current when receiving the much larger negative voltage of anode 14 during 10 the idling period. The current then flowing through device 91 is preferably limited by a resistance 92. Such resistance does not appreciably affect the charge of condenser 64 provided that the ohmic drop caused within such resistance by 15 the current flowing over rheostat 33 be maintained at a negligible value.

In operation, during the idling period of anode 14, device 91 carries current and maintains anode 26 at a voltage which is negative with respect to 20 the voltage of cathode 28 by the value of the discharge drop within device 91. Device 27 therefore does not carry current during such period. During the active period of anode 14, neglecting the current flowing over rheostat 33, it will be 25 seen that condenser 64 is gradually charged during the successive periods of current flow in anode 14, at a rate depending upon the value of resistance 92. As shown in Fig. 7 the arc drop shown by curve 48 usually presents a maximum or peak 30 value during a portion of the current carrying period of the anode. When the arc drop reaches such value condenser 64 is charged correspondingly, and as such condenser cannot discharge over device 27, it will maintain its charge from 35 one cycle to the next. The voltage between cathode 28 and conductor 18 is then represented by the difference of the ordinates of line 92 passing through the peaks of curve 48 and of line 51 representing the arc drop within device 27. As 40 set forth above, the current flowing through resistance 33 is too small to cause condenser 64 to discharge appreciably between peaks of curve 48 but the flow of such current through device 27 tends to maintain the arc drop therein at a 45 stable value. In addition, resistance 33 provides a path for the partial discharge of condenser 64 when the arc drop within device 16 changes from one value to another and lower value.

In Fig. 9, curve 90 represents the value of the 50 plate current of device 67 plotted against the value of the grid voltage of such device for a predetermined value of the resistance in the plate circuit. In the embodiment illustrated in Fig. 4 it may be assumed that the voltage of grid 66 is negative 55 relative to the voltage of the cathode and is represented in magnitude by the distance OA consisting of the negative voltage OB of condenser 64 plus the voltage BA of battery 72. The current flowing through coils 74, 76 and 77 is 60 then represented by ordinate AC of curve 90. Assuming that the voltage drop in device 16 increases above the normal value thereof, condenser 64 becomes charged at a higher voltage represented in Fig. 9 by distance OD and the voltage 65 of grid 66 is then represented by distance OE. The plate current of device 67 is thereby reduced to the value EF so that the cores of reactors 78, 79 and 81 become substantially desaturated. Such reactors then introduce, in the circuit of device 70 16, a voltage drop which causes the current flowing through such device to be reduced to such an extent that the voltage drop again decreases to the normal value thereof. If the increase of the voltage drop is due only to an increase in the 75 current of device 16, such increase of current will

cause solenoid 87 to receive an increased current from shunt 47 thereby increasing the pressure on carbon pile 86. The resistance in the circuit of coils 74, 76 and 77 is thereby decreased so that a current of sufficient value to saturate the cores of the reactors may continue to flow through the coils and the flow of current through device 16 is not decreased.

In the embodiment illustrated in Fig. 5, it is assumed that the operation of anodes 14 of device 16 is controlled by means of control electrodes 93. Each control electrode is energized over a resistance 97 from one of the star connected portions of the secondary winding 96 of a control transformer having a primary winding 94 energized from line 11. The control transformer 94, 96 may be constructed as a phase shifter to permit regulation of the flow of current within device 16. As is well known, such device may then operate as a rectifier to transmit power from line 11 to line 18, 19, or as an inverter to transmit power in the reverse direction. The energization of control electrodes 93 is automatically adjusted by means of a regulator 98 operable to vary the resistance in the connections of winding 94 with line 11.

The regulator is herein represented as being of the rocking sector type and being actuated by an armature 99 mounted on a spindle 101. Armature 99, which is movable between the pole pieces of an electromagnet core 102, is provided with a winding 103 which is connected in series with a winding 104 of the electromagnet to impart a torque to such armature upon energization of the windings. The core also has a second winding 106 energized from shunt 47. The torque imparted to spindle 101 is opposed by a spring 107 which prevents spindle 101 from rotating continuously and the tension of the spring is adjusted by a screw 108. Spindle 101 carries a hub 109 serving as fulcrum for a plurality of conductive sectors 111. Each sector is insulated from hub 109 and rocks on an arcuate contact path consisting of a plurality of conductive segments separated by insulation; each segment is connected with a portion of a tapped resistance 112. To simplify the drawing each sector is however represented as being directly in contact with the associated resistance. Each resistance 112 is connected between two conductors of line 11 so that each sector 111 serves as a movable tap to impress, on winding 94, voltages of variable phase with respect to the voltages of line 11. Such connections permit shifting of the phase of energization of control electrodes 93 to thereby regulate the amount of current carried by the associated anodes 14 as is well known in the art.

Assuming that device 16 is operating as a rectifier, curve 113 of Fig. 8 represents the voltage 60 between anode 14 and cathode 17 when the time of operation of anode 14 is delayed by the action of control electrode 93. Curve 113 includes portions GH over which the anode does not carry current although its voltage is positive with respect to that of cathode 17 and portions KL over which the anode carries current, which are similar to the positive portions of curve 48 in Fig. 7. The remaining portion LG is similar to the negative portion of curve 48. It will be seen that 65 the system must be made responsive to the voltage between anode 14 and cathode 17 over portions KL of curve 113 and not over portions GH, over which such voltage may be of considerably greater magnitude.

To obtain the above result grid 66 of device 67 must not be constantly operatively connected with the anode 14 considered, as such grid would then receive voltages corresponding to portion 5 GH of curve 113. Such result is avoided by connecting grid 66, over resistance 73 and bias battery 72, to resistance 92 already utilized in the embodiment illustrated in Fig. 4. In the present embodiment, for the reason that the positive 10 voltage between anode and cathode of device 16 may become very great, it is no longer possible to use a device 91 which would carry current during the positive period of anode 14 corresponding to curve portion GH, and which would 15 thereafter continue to carry current over the period corresponding to curve portion KL. Device 91 is preferably replaced by a device 114 of the same type as device 27, which may carry current only during the negative period of anode 20 14. During the period corresponding to portion GH, grid 66 receives through battery 72, a voltage which is substantially the voltage of conductor 18 by the connection of resistance 92 with the anode 124 of a device 121 similar to device 25 67. The cathode 126 of such device is connected with conductor 18 and the grid 119 thereof is connected with cathode 126 over a resistance 123, a bias battery 122, and a portion of a rheostat 117. Rheostat 117 is energized from a current 30 transformer 116 inserted between winding 13 and anode 14. The plate circuit of device 67 is closed over battery 82, rheostat 83 and coils 103 and 104, so that the position of regulator 98 is determined by the average magnitude of the plate 35 current in device 67.

As is well known the voltage impressed on rheostat 117 from current transformer 116 may be represented by a curve 118 referred to axis 115 in Fig. 8. The voltage between grid 119 and 40 cathode 126 may then be represented, at a different scale, by the same curve 118 referred to another axis 120. During the period corresponding to curve portion GH, grid 119 thus has a slightly negative voltage with respect to cathode 126, represented by point A in Fig. 9, and permits flow of 45 current from anode 124 to cathode 126. The voltage between anode 14 and cathode 17 then appears at the terminals of resistance 92 and the only potential applied on grid 66 is that of battery 72, provided that the impedance of device 121 be small as compared with resistance 92. Such voltage may be represented by distance OM in Fig. 9, corresponding to the lower knee of curve 90. At the time corresponding to point H, K in 50 Fig. 8, the voltage of current transformer 116 reverses so that the voltage of grid 119 reached a value represented by point B sufficiently negative to interrupt the flow of current through device 121. Grid 66 is then energized from anode 14 55 over resistance 92, battery 72 and resistance 73.

The average voltage of grid 66 during interval KL is then represented by distance OE in Fig. 9 and the current flowing through windings 103 and 104 is represented by ordinate EF. If the arc 60 drop within device 16 increases, the average voltage of grid 66 becomes less negative and reaches a value represented by OA for which the current in windings 103 and 104 is represented by ordinate AC. Regulator 98 therefore rotates in such 65 a direction as to retard the time of positive energization of control electrodes 93, thereby causing the current within device 16 to decrease to an extent sufficient to reduce the average arc drop to the normal value thereof. If the increase of 70 75 arc drop was caused by an increase of current,

winding 106 receives an increased current from shunt 47 thereby opposing the effect of the current increase in windings 103 and 104. Armature 99 will therefore tend to remain in the position which it occupied previously and the flow of current will not be affected by the regulator. By suitable adjustment of spring 107 by means of screw 108, the regulator may also be so adjusted as to move only when windings 103 and 104 receive a current corresponding to an excessive arc drop within device 16. Such regulator will then be without effect on the flow of current as long as the average arc drop within device 16 remains normal.

In the embodiment illustrated in Fig. 6, device 121 is omitted and device 67 is replaced by a device 129 of the gas or vapor type having the anode 132 thereof connected with anode 14 over battery 25 and resistance 135. The cathode 133 of the device is then connected with conductor 18 over 20 windings 103 and 104. The voltage applied to the device during the idling or negative period of anode 14 may again be applied to resistance 135 by short circuiting device 129 over device 114. During the period corresponding to curve portion 25 GH in Fig. 8, the grid 131 of device 129 is maintained negative with respect to cathode 133, because grid 131 and battery 122 are herein connected with rheostat 117 in a manner opposite to that illustrated in Fig. 5 to obtain a grid voltage 30 represented by curve 125 in Fig. 8. At a time corresponding to point H, K in Fig. 8, grid 131 then becomes positive with respect to cathode 133 and permits the flow through device 129 of a current by the same process as the flow of current through device 27 in the embodiment illustrated in Fig. 1. Such current is again in proportion to the average value of the arc drop within device 16. At the end of each active period of anode 14, the voltage between anode 132 and 40 cathode 133 reverses so that device 129 is without current and grid 131 is again capable of retarding the flow of current through device 129 until anode 14 again carries current. The control of regulator 98 is thus obtained in a manner similar to 45 that described with respect to Fig. 5.

In the embodiment illustrated in Fig. 10, winding 94 is directly connected with line 11 and the adjustment of the control electrodes is obtained by means of a variable positive direct current bias 50 voltage. In the present embodiment, anode 14 is no longer connected with grid 66 over battery 72 and resistance 73 but is connected over a battery 139 and a resistance 141 with the grid 138 of a discharge device 134 similar to device 67. The cathode 142 of device 134 is connected with conductor 18 over condenser 64, this connection being similar to that of device 27 of the embodiment illustrated in Fig. 4. The anode 136 of device 134 is energized from battery 82 over a 60 rheostat 137. The heating circuit of cathode 69 of device 67 includes a regulator 143 similar to regulator 84 but differing from the latter in that regulator 143 is provided with a solenoid 144 tending to release the pressure applied to the 65 carbon pile 86 by a spring 146.

The operation of devices 114 and 121 remain substantially as described with respect to the embodiment illustrated in Fig. 5. During the active period of anode 14, grid 138 receives the voltage 70 of battery 139, the arc drop in device 16 and the voltage condenser 64. When the system is connected as shown, and anode 14 begins to carry current during a cycle of its operation, condenser 64 is not charged, and grid 138 is more positive 75

than the value OM of Fig. 9 with respect to cathode 142 so that a comparatively large current flows through device 134 from battery 82 over rheostat 137. The flow of such current gradually charges condenser 64 in such a manner that the condenser plate connected with cathode 142 becomes positive and the plate of such condenser connected with conductor 18 becomes negative. The voltage of condenser 64, being also inserted in the circuit between cathode 142 and grid 138, causes grid 138 to become increasingly negative by the amount of the voltage of condenser 64. Due to such variation of the voltage of grid 138, the current through device 134 gradually decreases and reaches a very small value when the device 134 operates on the lower knee of its characteristic at point M in Fig. 9. Such point corresponds to a condenser voltage OB, a bias voltage BP and an arc drop PM. Beyond the point 20 M, device 134 is not entirely non-conductive and a small current would continue to flow, thereby slowly changing the voltage of condenser 64. The voltage of the condenser is preferably stabilized by permitting the small current represented by 25 ordinate MN in Fig. 9 to leak over resistance 33, thereby maintaining point M as operating point of device 134. The voltage of condenser 64, represented by distance OB, is impressed on grid 66 of device 67 in a manner opposite to that previously described with respect to the embodiment illustrated in Fig. 4. For the particular value 30 PM of the arc drop in device 16, the condenser 64 receives voltage OB which brings grid 66 to voltage OE, thereby causing the flow of a predetermined amount of current EF through device 67 from battery 82 over rheostat 83. Battery 82 also supplies, over rheostat 83, another current which flows over a resistance 147, thereby brings the neutral point of winding 96 to positive potential 35 with respect to the potential of cathode 17. The phase relation between windings 13 and 96 is so chosen that control electrode 93 becomes positive with respect to cathode 17 at the desired moment to permit flow of current through anode 14. 40 If the arc drop in device 16 increases, the voltage of condenser 64 increases thereby bringing the grid 66 of device 67 to the value OA less negative with respect to cathode 69. The impedance of device 67 is thus decreased and a larger current 45 flows through such device. The voltage drop in rheostat 83 caused by the flow of such current then increases which results in a decrease of the flow of current in rheostat 147 and therefore in a decrease of the voltage drop in such resistance. 50 The positive bias impressed on control electrode 93, which is equal to such voltage drop, is thus decreased and the moment of the voltage cycle at which control electrode 93 becomes positive is thereby retarded. As is well known such retardation results in a decrease of the current in device 16. If, however, the increase of the arc drop results from an increase in the current carried by device 16, solenoid 144 receives an increased current from shunt 47. The action of 55 the solenoid causes a lesser pressure to be applied to carbon pile 86 and the resistance of such carbon pile increases. The heating current of cathode 69 is thereby decreased, such action tending to increase the impedance of device 67 60 and thus neutralizing the effect of the change of voltage of grid 66. Under such conditions the bias voltage applied to control electrode 93 will not change and the flow of current in device 16 will not be altered.

75 Although but a few embodiments of the pres-

ent invention have been illustrated and described, it will be apparent to those skilled in the art that various changes and modifications may be made therein without departing from the spirit of the invention or from the scope of the appended 5 claims.

It is claimed and desired to secure by Letters Patent:

1. The combination with an electric current supply circuit, an electric current load circuit, 10 and an electron discharge device comprising an anode and a cathode interconnecting said circuits and constituting spaced electrodes for the flow of current therebetween, of means operable responsive to variations in the magnitude of the 15 voltage drop only between said electrodes for controlling the operation of said device.

2. The combination with an electric current supply circuit, an electric current load circuit, 20 and an electron discharge device comprising an anode and a cathode interconnecting said circuits and constituting spaced electrodes for the flow of current therebetween, of means operable responsive to variations in the magnitude of the voltage drop of unidirection only between said electrodes for 25 controlling the operation of said device.

3. The combination with an electric current supply circuit, a load circuit, an electron discharge device comprising an anode and a cathode interconnecting said circuits and constituting 30 spaced electrodes for the flow of current therebetween, and means operable to control the said flow of current between said electrodes, of means operable responsive to variations in the magnitude of the potential difference of unidirection 35 only between said electrodes for controlling the operation of said device.

4. The combination with an electric current supply circuit, a load circuit, an electron discharge device comprising an anode and a cathode interconnecting said circuits and constituting spaced electrodes for the flow of current therebetween, and means for controlling the flow of current between said electrodes, of means operable 40 responsive to variations in the average value of the voltage drop only between said electrodes for controlling the operation of the first said means.

5. The combination with an electric current supply circuit, a load circuit, and an electron discharge device comprising an anode and a cathode interconnecting said circuits and constituting spaced electrodes for the flow of current therebetween, of means operable responsive to variations in the potential difference of unidirection only 50 between said electrodes for controlling the operation of said device.

6. The combination with an electric current supply circuit, an electric current load circuit, and an electron discharge device comprising an anode and a cathode interconnecting said circuits and constituting spaced electrodes for the flow of current therebetween, of means connected with said electrodes and operable responsive to the voltage drop therebetween for affecting the operation of said device, an electron discharge device having spaced electrodes included in said connections of said means operable to limit the response of the latter to periods during which current flows between the first said electrodes, means for producing operating vapor within the second said device, thermally actuated means for affecting the operation of the second said means, and means connected with one of said circuits and operable responsive to and in dependence upon the magni- 75

tude of current flowing therein for causing actuation of the third said means.

7. The combination with an electric current supply circuit, a load circuit, and an electron discharge device of the vapor arcing type comprising an anode and a cathode interconnecting said circuits and constituting spaced electrodes for the flow of current therebetween, of thermal means for producing operating vapor within said device, 10 means connected with said electrodes and operable responsive to the voltage drop therebetween for affecting the operation of the first said means, and an electron discharge device included in the connection of the second said means operable to 15 limit the response thereof to periods during which current flows between said electrodes.

8. The combination with an electric current supply circuit, a load circuit, and an electron discharge device of the vapor arcing type comprising 20 an anode and a cathode interconnecting said circuits and constituting spaced electrodes for the flow of current therebetween, of thermal means for producing operating vapor within said device, means connected with said electrodes and 25 operable responsive to the voltage drop therebetween for affecting the operation of the first said means, an electron discharge device of the vapor type included in the connection of the second said means operable to limit the response 30 thereof to periods during which current flows between said electrodes, means for producing operating vapor within the second said device, thermally actuated means for affecting the operation of the third said means, and means connected 35 with one of said circuits and operable responsive to and in dependence upon the magnitude of the current flowing therein for causing actuation of the fourth said means.

9. The combination with a polyphase alternating current supply circuit, an electric current load circuit, and an electron discharge device comprising a plurality of anodes and a cathode interconnecting said circuits and constituting spaced electrodes for the flow of current through 45 said device from said supply circuit to said load circuit, of means for regulating the said flow of current comprising a plurality of inductors having windings severally included in the connections of the conductors of said supply circuit with said 50 device, means for variably exciting said inductors to thereby vary the inductance thereof, means for energizing the second said means, and means comprising an electron discharge device having connections with said cathode and with one of 55 said anodes operable responsive to and in dependence on the voltage drop therebetween for controlling the operation of the third said means, whereby the inductances of said inductors are varied and the flow of current through the first 60 said device thereby regulated.

10. The combination with a polyphase alternating current supply circuit, an electric current load circuit, and an electron discharge device comprising a plurality of anodes and a cathode 65 interconnecting said circuits and constituting spaced electrodes for the flow of current through said device from said supply circuit to said load circuit, of means for regulating the said flow of current comprising a plurality of inductors 70 having windings severally included in the connections of the conductors of said supply circuit with said device, means including a source of current and an auxiliary winding for each of said inductors for exciting the latter, means comprising an electron discharge device included in

the connections of said source with said auxiliary windings operable to control the flow of current through the latter, means for controlling the operation of the second said device, and means comprising an electron discharge device having connections with said cathode and with one of said anodes operable responsive to and in dependence on the voltage drop therebetween for controlling the fourth said means, whereby the flow of current through the said auxiliary windings is varied 10 and the flow of current through the first said device thereby regulated.

11. The combination with a polyphase alternating current supply circuit, an electric current load circuit, and an electron discharge device 15 comprising a plurality of anodes and a cathode interconnecting said circuits and forming spaced electrodes for the flow of current therebetween, of means for regulating the said flow of current comprising a plurality of inductors having windings severally included in the connections of the conductors of said supply circuit with said device, means for variably exciting said inductors, means for energizing the second said means, means comprising an electron discharge device having connections with said cathode and with one of said 20 anodes operable responsive to and in dependence on the voltage drop therebetween for controlling the operation of the third said means to thereby control the operation of the second said means, 25 and means having connection with said load circuit and with the third said means operable to control the latter in dependence upon the magnitude of the current flow in said load circuit whereby the flow of current through the second 30 said device is regulated in dependence upon the voltage drop between the cathode and an anode of the first device and in dependence of the magnitude of the current supplied therefrom to said 35 load circuit.

12. The combination with an alternating current supply circuit, an electric current load circuit, an electron discharge device comprising a cathode, a plurality of anodes and a plurality of control electrodes severally associated with said 45 anodes, means connecting said device with said circuits comprising a transformer winding operable to impress potentials on said anodes during such recurring moments and of such sign and magnitude as to cause the flow of current 50 sequentially through said anodes from said supply circuit to said load circuit, means connected with said supply circuit and with said control electrodes operable to impress alternating current potentials on the latter of such phase and 55 during such recurring moments relative to the potentials impressed on the associated said anodes as to control the moments of initiation of recurring flow of current through the latter, and means for varying the phase angle of said 60 potentials impressed on said control electrodes, of means connected with one of said anodes and said cathode operable responsive to the voltage drop therebetween during periods of flow of current 65 therebetween for controlling the operation of the third said means, and means having connection with one of said circuits and operable in dependence on the current flowing therein for controlling the operation of the third said means.

13. In a control system for electron discharge 70 devices, a supply line, an electron discharge device connected with said line, an output line connected with said device, means responsive to the peak value of the voltage drop in said device, means for controlling the flow of current 75

through said device, and means controlled by the first said means to control the second said means.

14. In a control system for electron discharge devices, a supply line, an electron discharge device connected with said line, an output line connected with said device, means responsive to the value of the voltage drop in said device, means for interrupting the flow of current through said device, and means controlled by the first said means to cause operation of the second said means when the voltage drop within said device exceeds a predetermined value.

15. In a control system for electron discharge devices, a supply line, an electron discharge device connected with said line, an output line connected with said device, means responsive to the value of the voltage drop in said device, means for controlling the operation of said device, and means controlled by the first said means to cause operation of the second said means when the voltage drop within said device exceeds a predetermined value.

16. In a control system for electron discharge devices, a supply line, an electron discharge device connected with said line, an output line connected with said device, means responsive to the value of the voltage drop in said device, means for controlling the operation of said device, means controlled by the first said means to control the second said means, and means responsive to the flow of current through said device to adjust the operation of the first said means.

17. In a control system for electron discharge devices, a supply line, an electron discharge device connected with said line, an output line connected with said device, means responsive to the value of the voltage drop in said device, means for controlling the operation of said device, means controlled by the first said means to control the second said means, and means responsive to the flow of current through said device to adjust the operation of the second said means.

18. In a control system for electron discharge devices, a supply line, an electron discharge device connected with said line, an output line connected with said device, means responsive to the value of the voltage drop in said device, a circuit breaker in said supply line, and means responsive to operation of the first said means for causing operation of said circuit breaker when the voltage drop within said device exceeds a predetermined value.

19. In a control system for electron discharge devices, a supply line, an electron discharge device connected with said line, an output line connected with said device, means responsive to the value of the voltage drop in said device, means producing operating vapor within said device, and means responsive to operation of the first said means for causing operation of the second said means when the voltage drop within said device exceeds a predetermined value.

20. In a control system for electron discharge devices, a supply line, an electron discharge device connected with said line and having electrodes, an output line connected with said device, means connected with two of said electrodes and receiving current only when current flows therebetween, and means controlled by said means to regulate the flow of current through said device.

21. In a control system for electron discharge devices, a supply line, an electron discharge de-

vice connected with said line and having electrodes, an output line connected with said device, means connected with two of said electrodes and receiving current from said supply line only when current flows between said two of said electrodes, and means controlled by said means to reduce the flow of current through said device when the voltage drop between said two of said electrodes exceeds a predetermined value during periods of flow of current therebetween.

22. In a control system for electron discharge devices, a supply line, an electron discharge device connected with said line and having electrodes and current controlling means, an output line connected with said device, means connected with two of said electrodes and receiving current from said supply line only when current flows between said two of said electrodes, and means controlled by the second said means to control the operation of said current controlling means.

23. In a control system for electron discharge devices, a supply line, an electron discharge device connected with said line and having electrodes, an output line connected with said device, an electron discharge device connected with two of the electrodes of the first said device, the second said device receiving current only when current flows between the said two of the electrodes, and means responsive to the flow of current through the second said device to control the operation of the first said device.

24. In a control system for electron discharge devices, a supply line, an electron discharge device connected with said line and having electrodes, an output line connected with said device, an electron discharge device connected with two of said electrodes and receiving current from said supply line only when current flows between the said two of said electrodes, and means responsive to the flow of current through the second said device to regulate the flow of current through the first said device.

25. In combination with an electric current supply circuit, an output circuit, and an electron discharge device having electrodes constituting arcing terminals for the flow of current through said device from said supply circuit to said output circuit, of means for controlling the operation of said device, means connected with and responsive to the voltage drop above a predetermined value between two of said electrodes for controlling the operation of the first said means, and an electron discharge device included in the said connection of the second said means operable to limit the said response of the latter to periods during which current flows between the said two of said electrodes.

26. In combination with an electric current supply circuit, an output circuit, and an electron discharge device comprising electrodes constituting arcing terminals for the flow of current through said device from said supply circuit to said output circuit, means for producing and ionizing vapor within said device, means connected with and responsive to the voltage drop above a predetermined value between two of said electrodes for affecting the operation of the first said means, and an electron discharge device included in the said connection of the second said means operable to limit the response of the latter to periods during which current flows between the said two of said electrodes.

27. In combination with an electric current

supply circuit, an output circuit, an electron discharge device having a plurality of electrodes constituting arcing terminals for the flow of current through said device from said supply circuit to said output circuit, and means comprising an excitation electrode disposed within said device for producing and maintaining ionized vapor therein, of means connected with and responsive to the voltage drop above a predetermined value between two of said plurality of electrodes for affecting the operation of the first said means, and an electron discharge device included in the said connection of the second said means operable to limit the response thereof to 15 periods during which current flows between the said two of said electrodes.

28. In combination with an electric current supply circuit, an output circuit, and an electron discharge device comprising electrodes constituting arcing terminals for the flow of current through said device from said supply circuit to said output circuit, of means for producing operating vapor within said device, means connected with two of said electrodes and responsive to the voltage drop therebetween above a predetermined value for affecting the operation of the first said means, an electron discharge device having electrodes included in said connections of the second said means operable to limit the response of the latter to periods during which current flows between the said two of said electrodes, means for producing operating vapors within the second said electron discharge device, and means connected with said output circuit operable responsive to and in dependence upon the magnitude of the current flowing therein for varying the operation of the third said means.

29. In a system of the character described, an alternating current supply circuit, an output circuit, an electron discharge device comprising a cathode, a plurality of anodes and a plurality of control electrodes severally associated with said anodes, means connecting said device with said circuits comprising a transformer winding operable to impress potentials on said anodes during such recurring moments and of such sign and magnitude as to cause the flow of current sequentially through said anodes from said supply circuit to said output circuit, means connected with said supply circuit and with said control electrodes operable to impress alternating current potentials on the latter of such phase and magnitude and during such recurring moments relative to the potentials impressed on the associated said anodes as to control the moments of initiation of recurring flow of current through the latter, means for varying the phase angle of the said potentials impressed on said control electrodes, and means connected with one of said anodes and said cathode operable responsive to the voltage drop therebetween during periods of flow of current therebetween for controlling the operation of the third said means.

30. In a system of the character described, an alternating current supply circuit, an output circuit, an electron discharge device comprising a cathode, a plurality of anodes and a plurality of control electrodes severally associated with said anodes, means connecting said device with said circuits comprising a transformer winding operable to impress potentials on said anodes during such recurring periods and of such sign and magnitude as to cause the flow of current sequentially through said anodes from said supply circuit to said output circuit, means connected with said

supply circuit and said control electrodes operable to impress alternating current potentials on the latter of such phase and magnitude and during such recurring moments relative to the potentials impressed on the associated said anodes 5 as to control the moments of initiation of recurring flow of current through the latter, means for varying the phase angle of the potentials impressed on said control electrodes, means connected with one of said anodes and said cathode 10 and receiving current from said supply circuit in dependence upon the magnitude of the voltage drop between the said one of said anodes and said cathode for controlling operation of the third said means, and an electron discharge device included in the said connections of the fourth 15 said means operable to limit the flow of current therethrough to periods during which current flows between the said one of said anodes and said cathode. 20

31. The combination with an electron discharge device comprising an anode and a cathode constituting spaced electrodes for the flow of current therebetween, of means for measuring the voltage drop between said electrodes comprising an 25 indicating device having connections therewith and responsive to the voltage drop only therebetween.

32. The combination with an electron discharge device comprising an anode and a cathode 30 constituting spaced electrodes for the flow of current therebetween, of means for measuring the voltage drop between said electrodes comprising an indicating device having connection therewith and responsive to the potential difference 35 only therebetween, and means operable to limit the response of said indicating device to periods during which current flows between said electrodes.

33. The combination with an electron discharge device comprising an anode and a cathode constituting spaced electrodes for the flow of current therebetween, of means for measuring the voltage drop between said electrodes comprising an indicating device having connection therewith and responsive to the potential difference 45 only therebetween, and an electron discharge device comprising electrodes included in the said connection and operable to limit the response of said indicating device to periods during which 50 current flows between the first said electrodes.

34. The combination with an electron discharge device comprising an anode and a cathode constituting spaced electrodes for the flow of current therebetween, of means for measuring the voltage drop between said electrodes comprising an indicating device having connection therewith and responsive to the potential difference only 55 therebetween, and means operable to limit the response of said indicating device to said potential difference of unidirection only.

35. The combination with an electron discharge device comprising an anode and a cathode constituting spaced electrodes for the flow of current therebetween, of means for measuring the voltage drop between said electrodes comprising an indicating device having connection therewith and responsive to the potential difference only therebetween, and an electron discharge device having spaced electrodes included in said 65 connection and operable to limit the response of said indicating device to said potential of unidirection only and to periods during which current flows between the first said electrodes.

36. The combination with an electron dis- 75

- charge device comprising an anode and a cathode constituting spaced electrodes for the flow of current therebetween, of means for measuring the voltage drop between said electrodes comprising an indicating device having connection therewith and responsive to the potential difference only therebetween, means controlling the response of said indicating device comprising an electron discharge device having spaced electrodes included in said connection, and means for regulating the conductivity of the second said electron discharge device.
37. The combination with an electron discharge device comprising an anode and a cathode constituting spaced electrodes for the flow of current therebetween, of means for controlling the said flow of current, means for measuring the voltage drop between said electrodes, and means comprising an electron discharge device having spaced electrodes connecting the first said electrodes with the first and second said means and operable to limit the response thereof to the potential difference of unidirection only between the first said electrodes.
38. The combination with an electron discharge device comprising an anode and a cathode constituting spaced electrodes for the flow of current therebetween, of means for controlling said flow of current, means for measuring the voltage drop between said electrodes, and means comprising an electron discharge device having spaced electrodes connecting the first said electrodes with the first and second said means and operable to limit the response thereof to the potential difference of unidirection only between the first said electrodes and to periods during which current flows between the first said electrodes.
39. The combination with an electron discharge device comprising an anode and a cathode constituting spaced electrodes for the flow of current therebetween, of means for regulating the voltage drop between said electrodes, means for measuring said voltage drop, and means comprising an electron discharge device having spaced electrodes connecting the first said electrodes with the first and second said means and operable to limit the response thereof to the potential difference of unidirection only between the first said electrodes and to periods during which current flows therebetween.
40. The combination with an electron discharge device comprising an anode and a cathode constituting spaced electrodes for the flow of current therebetween, of means for measuring the voltage drop between said electrodes comprising an indicating device having connection with said electrodes and responsive to the potential difference only therebetween, means comprising an electron discharge device having spaced electrodes included in the connection of the first said electrodes with said indicating device and operable to limit the response thereof to periods during which current flows between the first said electrodes, and means operable in dependence upon the flow of current between the first said electrodes for regulating the conductivity of the second said electron discharge device.
41. In a control system for electron discharge devices, a supply line, an electron discharge device connected with said line, an output line connected with said device, means responsive to the value of the voltage drop only in said device including time delay means operable to retard the response of said voltage responsive means to

variations in the said voltage drop, means for controlling the flow of current through said device, and means controlled by the said voltage responsive means for controlling said current controlling means.

42. In a control system for electron discharge devices, a supply line, an electron discharge device connected with said line, an output line connected with said device, means responsive to the value of the voltage drop only in said device, means for controlling the flow of current through said device, and means controlled by said voltage responsive means operable to cause operation of said current controlling means including time delay means for retarding the operation of said current controlling means in response to variations in the value of said voltage drop.

43. In a control system for electron discharge devices, a supply line, an electron discharge device connected with said line, an output line connected with said device, means responsive to the value of the voltage drop only in said device, means for controlling the flow of current through said device, means controlled by said voltage responsive means for controlling said current controlling means, and time delay means responsive to the magnitude of the flow of current through said device to adjust the operation of said voltage responsive means, whereby said operation is variably adjusted in dependence upon the rate of change of the said flow of current through said device.

44. The combination with an electron discharge device comprising electrodes operable for the flow of current therebetween, of means for measuring the voltage drop between said electrodes comprising an indicating device responsive to the potential difference therebetween, means connected with said indicating device for controlling the response thereof, and means for controlling the action of said response controlling means to prevent the response of said indicating device during a period immediately preceding a period of current flow between said electrodes.

45. The combination with an electron discharge device comprising electrodes operable for the flow of current therebetween, of means for measuring the voltage drop between said electrodes comprising an indicating device responsive to the potential difference therebetween, means connected with said indicating device for controlling the response thereof, and means operable in dependence upon the flow of current between said electrodes for controlling the action of said response controlling means.

46. The combination with an electron discharge device comprising electrodes operable for the flow of current therebetween, of means for measuring the voltage drop between said electrodes comprising an indicating device responsive to the potential difference therebetween, means comprising an auxiliary electron discharge device connected with said indicating device for controlling the response thereof, and means operable in dependence upon the flow of current between said electrodes for controlling the conductivity of said auxiliary electron discharge device.

47. The combination with an electron discharge device comprising electrodes operable for the flow of current therebetween, of means for measuring the average value of the voltage drop between said electrodes comprising an indicating device connected with said electrodes and responsive to the potential difference therebetween,

means connected with said indicating device for controlling the response thereof, and means for controlling the action of said response controlling means to prevent the response of said indicating device during a period immediately preceding a period of current flow between said electrodes.

48. The combination with an electron discharge device comprising electrodes operable for the flow of current therebetween, of means for measuring the average value of the voltage drop between said electrodes comprising an indicating device connected with said electrodes and responsive to the potential difference therebetween, means connected with said indicating device for controlling the response thereof, means comprising an auxiliary electron discharge device connected with said indicating device for controlling the response thereof, and means operable in dependence upon the flow of current between said electrodes for

controlling the conductivity of said auxiliary electron discharge device.

49. The combination with an electron discharge device comprising electrodes operable for the flow of current therebetween, of means for measuring the average value of the voltage drop between said electrodes comprising an indicating device connected with said electrodes and responsive to the potential difference therebetween, means comprising an auxiliary electron discharge device connected with said indicating device for controlling the response thereof, and means operable in dependence upon the flow of current between said electrodes for controlling the conductivity of said auxiliary discharge device to limit the response of said indicating device to periods during which current flows between said electrodes.
